UNITED STATES PATENT OFFICE.

SOLOMON E. AARON, OF BOSTON, MASSACHUSETTS.

WIRE-STRIPPING PLIERS.

1,354,365.

Specification of Letters Patent. Patented Sept. 28, 1920.

Application filed April 17, 1919. Serial No. 290,842.

To all whom it may concern:

Be it known that I, SOLOMON E. AARON, a citizen of the United States, residing at Boston, in the county of Suffolk and State 5 of Massachusetts, have invented certain new and useful Improvements in Wire-Stripping-Pliers; and I do hereby declare the following to be a full, clear, and exact description of the invention, such as will enable others skilled in the art to which it 10 pertains to make and use the same.

This invention relates to hand tools and especially to a type of tools such as are ordinarily used by electricians and others to 15 facilitate the removal of insulation from various kinds of insulated wire and more particularly to expedite the removal of the jacket of what is technically known as "round lamp-cord" from the enveloped conductors.

It is one of the objects of the present invention to provide means which will enable the rapid removal of the enveloping jacket of round lamp-cord not only with rapidity 20 and accuracy but also with the least possible danger of mutilating the insulating or wrapping material which incloses the usual copper conductor or strands in the enveloped conductors.

Another object of the present invention is to provide means which will serve as a guide and which is adapted to be adjusted to operate upon so-called round lamp-cord wires of different sizes. Another object is to provide means operative for the above function and which may be readily applied to standard pliers, now constructed, or to be constructed, at a minimum expense and which at the same time is durable, substantial, 35 practicable and comparatively inexpensive, and further to provide means combining features to facilitate the splitting or slitting of the outer jacket and also to enable the stripping of the inner conductors with facility, rapidity, accuracy and neatness.

With the above and other objects in view as will become apparent to those versed in the art, the invention consists in the construction, the combination, and in details 40 and arrangement of parts as more particularly described hereinafter relative to the embodiment of the invention illustrated in the accompanying drawings.

Figure 1 is a side elevation of the im-

proved pliers looking at the side of the tool 55 with the improved splitters.

Fig. 2 is a plan view of the tool shown in Fig. 1.

Fig. 3 is a side elevation of the tool looking toward the jaw and

Fig. 4 is an end elevation of the pliers 60 looking toward the jaw and

Fig. 5 is a perspective view of one of the detached plates having the splitting and stripping means.

One of the common duties of electricians, linemen, electrical workers and others is to carefully expose the copper conductors or conducting strands indicated at S in Fig. 2, without mutilating or fracturing the conductors or strands and especially exposing the strands of one kind of electric wire commonly known as round lamp-cord indicated at C and in which there is embedded a pair of conductors or wires W. The cord C comprises an outer webbing of fabric sheath F within which there is a body or filler of rubber R enveloping the two wires W which are formed of any suitable outer jacket within which there is inclosed the copper conductors S. It is very desirable that the wires W be exposed and the insulating material removed to bare the wire conductors or strands S and especially to avoid cutting, scraping, fracturing, or severing these metallic strands. To that end I have provided improved means shown in combination with a pair of common pliers having the usual handles 2 and 3 which are respectively pivoted at 4 and provided at the opposite ends 50 with upper and lower or opposed jaws 5 and 6 which have meeting faces 7-7. The hubs of the levers are shown at 8. The meeting faces of the jaws are recessed as at 9 and transversely disposed across one side 55 of the recess and at the side of the jaws 5-6 are arranged the usual side cutters 10-10 having edges in the meeting plane 10 of the jaws 5-5. In the practical use of the tool a piece of so-called cord or other electrical wire may be readily cut in the usual manner by transverse insertion between the side cutters 10-10 which are brought together by pressure applied in the usual manner to the handles 2-3.

To provide for the rapid and effective splitting of a piece of electrical wire shown herein as of the round lamp-cord type, the

pliers are provided with a set of blades 11-11, each of which extends relatively transversely from its respective face of the jaw 5 or 6 and with the blade also likewise 5 perpendicular, preferably to the meeting plane or faces 7-7 of each jaw. Each blade 11, which obviously may be of any length 11, which obviously may be of any length with respect to its projection from the side of the jaw, is provided with a relatively 10 deep notch leaving at each side a lip 12, the opposing edges of which, at opposite sides of the notch are preferably shaped on a re-entrant curve, and thus forming in each blade 11, one-half of a mouth which is 15 formed when both of the blades are brought into meeting position by the closure of the jaws 7. As shown, the inner edges of the lips define a notch with initially convergent side walls, and located centrally between 20 the side walls of the lips and projecting from the center or apex of each notch so as to substantially bisect it is a tooth or splitting means 14 which, as shown, is of less length than the depth of the notch defined 25 by the inner edges of the lips 13, so that when the blades 11-11 are brought together to a distance which is determined by any suitable adjusting device, as, for instance, the screw 15 mounted in one of the levers 30 and adjacent to and in the rear of the pivot 4 which controls the closure of the levers toward each other, the insertion of the special teeth 14 into the jacket or envelop 35 of the guard F is so limited that it will not penetrate to and engage the metallic strands S when the cord has been placed between the jaws and is being pulled in the direction of the arrow so as to split the cord.

As clearly shown in Fig. 1, the central 40 splitting tooth 14 has its edge beveled rearwardly and inclined upwardly so as to present a sharp and readily cutting edge to the cord as the latter is drawn along the wire to rest between the blades 11-11 while they 45 are held closed.

It will be understood from the above that the round cord is embraced by the lateral prong or guide-like portions 13-13 and which form the mouth and thus guide and laterally support the body of the wire. The 50 diameter of the wire or cord being operated on will determine the degree of closure of the jaws and the blades 11 and then the screw 15 is adjusted so as to prevent the 55 jaws from closing to such an extent as would be likely to cause injury to the copper conductor or wires S.

Preferably the central tooth or cutting member 14 is flanked on each side by deeper 60 recesses 16 so as to permit the cutting tooth to enter readily to the desired depth and to enable the rapid drawing movement of the cord through the closed blades of the mouth. One advantage of this form of tooth and 65 blade construction is that the cutting tooth

can be tempered and hardened to a desired degree so as to insure their durability and strength.

I prefer that the improved wire handling tool also be provided with means for rapidly 70 and effectually removing the insulation W from around the individual conducting strands or wires S and for this purpose I provide on the opposite side of the plier jaws, blades indicated at 17 having their 75 transverse edges disposed perpendicular to the sides of the jaws and at about the plane of the meeting faces 7-7 and beveled as clearly shown at 18. To enable the effective use of the stripping means or blades on conductors of different sizes, I prefer that the edge of the blade 17 be provided with suitable notches 18' which differ in size to approximately fit wires of different diameters and thus when a wire is to be stripped of its 80 jacket or insulating wrapper it is inserted between a pair of closed stripping blades 17 and when these are closed together and wire pulled lengthwise of itself, the insulation will be removed and the bared wire drawn 85 through the respective aperture 18' into which it may have been inserted.

In order to properly center and guide the round cord when slitting the covering the 90 dimensions from side to side between the guide walls and the notches should not be greater than the dimensions along the line bisecting both notches when the blades are closed; and at such time of course the ends of the slitting points should be separated a 100 distance somewhat less than the width of the orifice so that they may penetrate a round conductor. By deepening the notches relatively to their width while still maintaining the distance between the slitting 105 points and particularly by also flaring the side walls slightly, as shown, the device is adapted to slit the covering of conductor cables of different diameters; and when so used the adjusting screw 15 will regulate the 110 penetration of the slitting points. The adjusting screw 15 will also be useful when the instrument is to be set for first slitting relatively large round conductors and for thereafter cleaning or stripping the wires. 115

I have illustrated the splitting and stripping means as made integrally of a piece of plate having a transverse bar portion 19, perforated as at 20 to receive a screw or other fastening means 21 by which the central 120 portion of the jaw may be clamped to the top surfaces of the plier jaws as clearly shown in Figs. 1 to 4 inclusive. The blades 11 and 17 are shown as bent forwardly and downwardly from the main jaw portion 19 125 as plainly shown in Fig. 5. This embodiment of the invention enables the splitting and stripping device to be readily applied to pliers already constructed and in use. Obviously my invention may be variously 130

incorporated in the construction of the pliers.

What I claim is—

1. Pliers having means for slitting the wrapping and the filler therein inclosing the usual conductors in "round lamp-cord," comprising a pair of plates, each plate having a blade bent to stand transverse to the side of a jaw and perpendicular to the meeting or 10 acting face thereof and having a lip shaped to form part of a mouth to laterally guide the cord drawn therethrough, and means for slitting the jacket of the cord as it passes the lip, said means comprising a central 15 tooth with its edge transverse to the length of the lip.
2. A pair of pliers having, in combination, a set of U-shaped plates with the ends of each bent transversely to the body portions 20 of the plates and adapted to form coöperating jaw members extending transversely on each side of the plier jaws, one of the bent ends of each plate having a central cutting tooth and side guide members for the purpose specified.
3. The combination of a pair of pliers, having opposed jaws, with coöperating blades attached to the jaws, one extending laterally from each side of each jaw, the 30 blades having coöperating guides and slitting points formed to guide and centrally slit round conductor cord when the jaws are closed on one side of the jaws and coöperating stripping means on the other.
35. 4. The combination of a pair of pliers, with a slitting and stripping plate attachable to the back of each jaw, each plate comprising spaced apart blades adapted to embrace the jaw, and a means whereby each 40 said plate may be secured to its respective jaw, the coöperating blades on one side of the jaws having guiding and slitting means so formed as to guide and centrally slit round conductor cord when the jaws are closed, and 45 the coöperating blades on the other side having wire stripping means.
5. The combination of a pair of pliers, having opposed jaws, with coöperating blades attached to the jaws, one extending laterally 50 from each side of each jaw, the blades having coöperating guides and slitting points on one side of the jaws formed to guide and centrally slit round conductor cord when the jaws are closed and coöperating stripping means on the other and an adjustable device 55 to limit the closing movement of the jaws

whereby they may be adjusted to slit the insulation and then strip or clean the wires.

6. An instrument for slitting the insulation-covering of round insulated conductors, comprising a pair of opposed members relatively movable toward and from each other, each opposed member having a notch, provided with guiding and centering sides, corresponding to and mating with the notch of the other, a slitting tooth projecting from the apex of each notch in the direction of a line substantially bisecting them, the dimensions of the notches along a line bisecting them when the opposed members are in contact being at least as great as their width, whereby the instrument is adapted to center and guide round insulated conductors with respect to the slitting teeth.

7. An instrument for slitting the insulation-covering of round insulated conductors, comprising a pair of opposed members relatively movable toward and from each other, each opposed member having a notch, provided with guiding and centering sides, corresponding to and mating with the notch of the other, a slitting tooth projecting from the apex of each notch in the direction of a line substantially bisecting them, the dimension of the notches along a line bisecting them when the opposed members are in contact being greater than their width, and the distance between the ends of the slitting teeth being less than the distance between said guiding and centering sides when said members are in contact.

8. An instrument for slitting the insulation-covering of round insulated conductors, comprising a pair of opposed members relatively movable toward and from each other, each opposed member having a notch provided with guiding and centering sides that diverge adjacent the meeting surfaces of the members, a slitting tooth projecting from the apex of each notch in the direction of a line substantially bisecting them, the dimension of the notches along a line bisecting them, when the opposed members are in contact being greater than their width, and the distance between the ends of the slitting teeth being less than the distance between said guiding and centering sides, and an adjustable device for limiting the approach of the opposed movable members.

In testimony whereof I affix my signature. 110

SOLOMON E. AARON.
